(57) **CLAIM**

The ornamental design for an elbow harness, as shown and described.

DESCRIPTION

FIG. 1 is a front, right perspective view of an elbow harness of the design;

FIG. 2 is a top view thereof;

FIG. 3 is a bottom view thereof;

FIG. 4 is a front elevation view thereof, the rear elevation view being the same;

FIG. 5 is a right elevation view thereof, the left elevation view being the same; and,

FIG. 6 is an environmental view thereof.

The broken lines are for the purpose of depicting environment and form no part of the claim.
